Design No. 12,002, dated October 26, 1880.

UNITED STATES PATENT OFFICE.

SILVIUS HURSEN, OF VICKSBURG, MICHIGAN.

DESIGN FOR A PICTURE-CHART.

SPECIFICATION forming part of Design No. 12,002, dated October 26, 1880.

Application filed July 12, 1879. Term of patent 7 years.

To all whom it may concern:

Be it known that I, SILVIUS HURSEN, of Vicksburg, in the county of Kalamazoo and State of Michigan, have invented and produced a new and original Design for Memorial Cards or Charts, of which the following is a specification, reference being had to the accompanying photograph, forming a part thereof.

The leading feature of my design consists in ornamenting the face of the card or chart with scroll-work, and placing in the said scroll-work openings in which to insert the likeness of a person or persons to be remembered. The openings are oval shaped, being four in number, and placed, respectively, one at the upper middle, and one at the lower middle, of the chart or card, and one each between and at the sides of the said openings A A.

At the sides of the openings A and the ends of the openings B are represented plates upon which to inscribe the name, age, birth, or marriage of the person or persons whose picture is placed in the said openings. Encircling the openings A is represented scroll-work in the form of leaves, which terminates at each corner of the card or chart in the form of rosettes.

In the center of the card and between the openings the upper half of the scroll-work is U-shaped, while the lower half is in the shape of an inverted U, having pendent from the inner center of both scroll-work representing leaves.

Above and below the plates of the ovals B, respectively, are represented leaves of separate scroll-work. The space between the U and the inverted U is partially filled by a figure corresponding to a double-lifting handle, rounded at its ends and attached at its middle to the head of an implement, as shown.

I claim—

The memorial card or chart herein shown and described, consisting of the scroll-work representing leaves and rosettes, one, respectively, upon each of the four corners of the card, openings A and B, plates C, and the figure D, all substantially as shown and described.

SILVIUS HURSEN.
